UNITED STATES PATENT OFFICE.

SOLOMON GILBERT TOUCHSTONE, OF COLUMBIA, SOUTH CAROLINA

TENSION FEELER.

Application filed May 2, 1924. Serial No. 710,605.

To all whom it may concern:

Be it known that I, SOLOMON G. TOUCHSTONE, a citizen of the United States, residing at Columbia, in the county of Richland 5 and State of South Carolina, have invented a new and useful Tension Feeler, of which the following is a specification.

This invention relates to a tension feeler, which is adapted to be used in connection 10 with slubbers, intermediates, speeders, roving machines, and other textile machinery.

In the operation of machines of this class, it sometimes happens that the contact gears or changing devices get out of order, or 15 from atmospheric changes, or through the tampering with the tensioning devices by unskilled help, the ends of the sliver become tighter than desired, resulting in uneven or 20 weak roving, thereby causing uneven or weak yarn to be produced.

The general object of the present invention is to provide improved automatic means for preventing this undesirable result, which is in the form of an attachment 25 adapted to shift the shipper rod, and to stop and lock the machine whenever the tension becomes too tight, so that it is impossible to operate the machine until the 30 tension has been properly adjusted. The invention is in the form of a feeler over which the sliver is drawn, and which may be readily attached to any of the machines now in use without any material alteration in the latter.

The specific construction of the invention and its application to textile machinery will be more particularly described in connection 35 with the accompanying drawings, which illustrate the invention in its preferred form.

40 In the drawings:

Figure 1 is a longitudinal section through the rear part of a roving machine having my invention applied thereto, with the third samson shown in elevation.

45 Figure 2 is a rear elevation of the invention.

Figure 3 is a front elevation of the portion of the machine to which the invention is attached.

50 Figure 4 is a sectional detail view of the feeler support.

Figure 5 is a detail view of the means by which the latch is operated.

Figure 6 is a detail sectional view taken on the line 6—6 of Figure 5. 55

Figure 7 is a perspective view of the feeler detached.

Figure 8 is a perspective view of the latch-engaging trip finger.

Figure 9 is a detail view of the feeler bar. 60

For the sake of illustrating the application of the invention to the textile art, I have shown it in connection with a roving machine of common construction, the machine being shown somewhat diagrammatically, and only those parts being shown which are necessary to a full understanding of the invention. The roll beam of the machine is denoted by the numeral 10, and the second and third samsons by the numerals 11 and 12, respectively. Top and bottom cones 13 and 14 are carried by shafts 15 and 16, which are suitably journaled in the frame of the machine, and may be driven in the usual manner. The cones 13 and 14 65 are connected by a belt 17, which is embraced by a fork 18 carried at the end of a bar 19, which in machines of this character is advanced longitudinally to vary the speed of the spindles. 70

The roving machine also includes a vertically reciprocating frame 20, one end of which is shown in Figure 1, guided on the track 21, and actuated by a rack 22 in mesh with a pinion 23 on the shaft 16. The end 75 of the frame 20 is counterbalanced by a weight 24 attached to a chain 25, which passes over sheaves 26 mounted on the samson and under a sheave 27 mounted on the 80 slideable frame, and has its end secured to the frame, as indicated at 28.

A shipper rod 30, shown in Figure 3, is adapted to be moved longitudinally in the direction indicated by the arrow for throwing the machine out of operation. This 85 shipper rod passes through an eye 31 formed on the upwardly extending arm of a swing lever 32, and has a stop or tappet 33 secured thereto, and normally in engagement with the swing lever, as shown in Figure 3, during the operation of the machine. The swing lever 32 is fulcrumed on a stud 34, which is mounted in a bracket 35 secured to the beam 10. The lever has a laterally extending arm 36 to which is adjustably secured a weight 37, which is suffi- 100 105

cient to swing the lever 32 and the shipper rod 30 longitudinally, and render the machine inoperative. The lever, however, is normally held with the arm 36 raised by means of a latch 38 pivoted to the lower end of the lever, and having a notched end 39 adapted to project through and engage a stop plate 40 secured to the samson 12. A tappet or knock-off 41 is, however, secured to the bar 19, and when the bar reaches the end of its movement, the knock-off 41 engages the inclined portion 42 of the latch and raises the same, thus releasing the latch and permitting the arm 36 of the lever 32 to swing downwardly and to effect an automatic stopping of the machine.

The mechanism thus far described is common in roving machines, and the latch 38 is usually raised to release the lever 32, and move the shipper rod 30 to throw the machine out of operation, only at the conclusion of the roving operation. The present invention, however, provides supplementary means for automatically releasing the latch 38 to permit movement of the shipper rod, whenever the tension of the sliver becomes greater than that for which the machine is set, thereby making further operation of the machine impossible until the tension of the machine is adjusted, and consequently making it impossible to produce an inferior, uneven yarn.

In the roving machine, a series of rolls 43 are supported above the roll beam, and in the roving operation, the sliver 44 is drawn from the rolls 43 to the nose of the flier. In carrying out my invention, I provide a feeler bar 45, over which the sliver 44 is drawn in its passage from the rolls to the flier. This feeler bar 45 is secured transversely to the extremity of an angular rod 46, which is supported at its other end by being screwed into a bearing member 47, journaled on a stud 48, which is mounted in a bracket 49 secured to the roll beam 10. Screwed into the opposite side of the bearing member 47 is the upper end of a rod 50, the lower end of which is turned laterally, as at 51, and provided with a loop 52. This loop receives and guides the lower portion of a trip finger 53, having its lower end formed with a laterally projecting tooth 54, which, under certain conditions, is adapted to engage underneath the projecting end 39 of the latch 38, and raise the same to stop the machine. The upper end of the rod 53 is offset, as at 55, and has a threaded connection with an eye 56, which may be adjusted longitudinally, and secured by means of a lock nut 57. The eye 56 is journaled on a wrist pin 58, projecting from an eccentric or crank disk 59 secured to one end of a shaft 60, which is journaled in a block 61, secured above the roll beam 10. During

the roving operation, the shaft 60 is slowly rotated by means of a worm gear 62 secured to its rear end, and driven by means of a worm 63 formed on either the front or rear roller 43.

The feeler bar 45 is held normally in engagement with the sliver 44 by a counterbalance 64, which is adjustably mounted on a rod 65, projecting forwardly from the bearing member 47. The initial adjustment of the counterbalance 64 is such that with the sliver 44 under normal tension, the feeler bar 45 will be held upwardly, as indicated by dotted lines in Figure 1, and the trip finger 43 will be held away from the latch 39, so that as the shaft 60 and eccentric 59 are slowly rotated, the trip finger will be raised and lowered without engaging the latch. In case the tension on the sliver 44, however, becomes tighter than it should be, the feeler bar is swung downwardly in opposition to the counterbalance 64, and the first subsequent upward movement of the trigger finger will cause the tooth 54 to engage the end 39 of the latch, and raise the same to release the shipper rod.

From the foregoing description, it will be seen that I have provided a device which can be readily attached to the roll beam of an ordinary roving machine in operative relation to the usual knock-off latch, and without any material alteration in the structure or operation of the machine. It is so arranged that it may be driven by one of the rolls between which the sliver passes, and is arranged so that whenever the tension on the sliver becomes tighter than it should be by reason of atmospheric changes, or from other causes, it will automatically stop the operation of the machine upon the next upward movement of the trip finger, and it will be impossible to operate the machine until it is adjusted.

While I have shown and described the invention as applied to a roving machine, it will be understood that this is merely for the purpose of illustration, and that the same is adapted to be applied to any similar machine used in the textile art. It will also be understood that the invention is not necessarily limited to the precise structure shown and described, but that modifications may be made in the size, shape and relative arrangement of the various elements of the device without departing from the salient features of the invention as claimed.

What is claimed is:

1. In a machine of the class described, the combination of a shipper rod, an arm movable to shift the same, a latch normally holding said arm against movement, a continuously driven reciprocating trip finger, means for guiding said trip finger so that it normally moves clear of the latch, and

means operable by the sliver when subjected to abnormal tension to swing said trip finger into a position so that its reciprocation will cause it to contact with and release said latch.

2. In a machine of the class described, the combination of a shipper rod, an arm movable to shift the same, a latch normally holding said arm against movement, a continuously driven reciprocating trip finger, a pivoted member having means for guiding the trip finger so that it normally moves clear of the latch and having a feeler portion over which the sliver is drawn, said pivoted member and guiding means being operable by an abnormal tension on the sliver to swing the trip finger into a position so that its reciprocation will cause it to contact with and release said latch.

3. In a machine of the class described, the combination of a stationary frame, rolls mounted thereon between which the sliver passes, a shipper rod, an arm movable to shift the same, a latch normally holding said arm against movement, a trip finger, means geared to one of the rolls for reciprocating the trip finger, means for guiding the trip finger so that it normally moves clear of the latch, and means operable by the sliver when subjected to abnormal tension to swing the trip finger into a position so that its reciprocation will cause it to engage with and release said latch.

4. In a machine of the class described, the combination of a shipper rod, an arm movable to shift the same, a latch normally holding said arm against movement, a continuously rotatable shaft having an eccentric secured thereto and provided with a wrist pin, a trip finger carried by and depending from the wrist pin, means for guiding said trip finger so that it normally moves clear of the latch, and means operable by the sliver when subjected to abnormal tension to swing said finger into such a position that its reciprocation will cause it to engage said latch and release the shipper rod.

5. In a machine of the class described, the combination of a shipper rod, a swing arm movable to shift the same, a latch normally holding said arm against movement, a continuously rotatable shaft having an eccentric secured thereto and provided with a wrist pin, a trip finger carried by and depending from the wrist pin, a pivoted member having means for guiding the trip finger so that it normally moves clear of the latch and having a feeler portion over which the sliver is drawn, said pivoted member and guiding means being operable by an abnormal tension on the sliver to swing the trip finger into such a position that its reciprocation will cause it to engage said latch and release the swing arm.

6. In a machine of the class described, the combination of a stationary frame including a roll beam, rolls journaled above said beam between which the sliver passes, a shipper rod, a swing arm movable to shift the same, a latch normally holding said arm against movement, a shaft geared to one of the rolls and having an eccentric secured thereto and provided with a wrist pin, a trip finger carried by and depending from the wrist pin, means for guiding said trip finger so that it normally moves clear of the latch, and means operable by the sliver when subjected to abnormal tension to swing said guiding means into such a position that the reciprocation of the finger will cause it to engage said latch and release the swing arm.

7. In a machine of the class described, the combination of a stationary frame including a roll beam, rolls journaled above said beam between which the sliver passes, a shipper rod, a swing arm movable to shift the same, a latch normally holding said arm against movement, a shaft geared to one of the rolls and having an eccentric secured thereto and provided with a wrist pin, a trip finger carried by and depending from the wrist pin, a member pivotally supported on the roll beam and carrying at one end a feeler bar over which the sliver is drawn and having its other end formed into a guide through which the trip finger passes, said member and guide normally holding the trip finger in such a position that it will move clear of the latch but operable by an abnormal tension on the sliver to swing the trip finger into such a position that its reciprocation will cause it to engage the latch and release the swing arm.

8. In a machine of the class described, the combination of a shipper rod, a swing arm movable to shift the same, a latch normally holding said arm against movement, a trip finger adjacent said latch, means connected with the upper end of the finger from which the finger depends and by which it is vertically reciprocated, means for guiding said trip finger so that it normally moves clear of the latch, and means operable by the sliver when subjected to abnormal tension to swing said guiding means into such a position that the reciprocation of the finger will cause it to engage said latch and release the swing arm.

9. In a machine of the class described, the combination of a shipper rod, a swing arm movable to shift the same, a latch normally holding said arm against movement, a trip finger adjacent said latch, means connected with the upper end of said finger from which the finger depends and by which it is vertically reciprocated, a pivoted member having means for guiding the trip finger so that it normally moves clear of the latch and hav-

ing a feeler portion over which the sliver is drawn, said pivoted means being operable by an abnormal tension on the sliver to swing said finger into such a position that its reciprocal action will cause it to engage the latch and release the swing arm, and a counter-balance on said pivoted member adjustable to vary the amount of tension on the sliver necessary to render the trip finger active. In testimony that I claim the foregoing invention as my own, I have hereto affixed my signature.

SOLOMON GILBERT TOUCHSTONE.
